[57] CLAIM

The ornamental design for a combined toy gun and carrying case, substantially as shown and described.

DESCRIPTION

FIG. 1 is a perspective view of a combined toy gun and carrying case showing our new design;

FIG. 2 is a top plan view thereof;

FIG. 3 is a front elevational view thereof;

FIG. 4 is a rear elevational view thereof;

FIG. 5 is a bottom plan view thereof;

FIG. 6 is an end view thereof, as viewed from the right of FIG. 3;

FIG. 7 is an end view thereof, as viewed from the left of FIG. 3; and

FIG. 8 is a front elevational view which illustrates our new design in an open condition.

FIG. 2

FIG. 6

FIG. 7
